UNITED STATES PATENT OFFICE.

WALTER WILLIAM WALKER GREEN, OF STAVERTON, ENGLAND.

BOX.

SPECIFICATION forming part of Letters Patent No. 740,009, dated September 29, 1903.

Application filed May 29, 1903. Serial No. 159,381. (No model.)

To all whom it may concern:

Be it known that I, WALTER WILLIAM WALKER GREEN, a subject of the King of Great Britain, residing at Staverton, in the county of Northampton, England, have invented certain new and useful Improvements in Boxes, of which the following is a specification.

The object of this invention is to construct a box or basket in such a manner that it can be employed as a table in addition to its ordinary use as a box, besides having articles attached to it for other purposes.

My invention will be understood from the following description, aided by the accompanying drawings, in which—

Figure 1 is an end view of a box arranged on a stand and with the back and the lid raised to form a table. Fig. 2 is a similar view to Fig. 1 with the back and lid closed and locked in the closed position. Fig. 3 is a side view of a box arranged on a stand and in which box the hinged back is made in two pieces, one being closed and the other open to form a table, one end being provided with means for hanging articles and the other with a wash hand-basin. Fig. 4 is an end view of Fig. 3.

According to this invention I take a box, and in addition to hinging the lid A, I hinge the back B, and I provide such lid and back with hinged rods C, these being notched at D E for engaging pins F, fitted on the inner ends G of the box for holding the lid and back in the closed or open position.

The box when required in use is arranged on a folding stand H, as shown in the figures, and such stand may be of any known construction and be part of the box or separate therefrom, as desired; but that which I prefer to employ is that shown on the drawings and consists of two sets of two strips of angle-iron H H', joined together at K, one strip, H, being provided with a lug L, which comes against the other strip, H', and limits the opening movement of both strips. Each set is connected together by bars M M', which pass from the bottom of one set of angle-irons to the top of the other set, crossing each other, the bars M M' being pivoted together at their crossing parts N. By this construction the angle-irons and bars can be readily folded to-

gether and will form a perfect stand when opened out.

According to Fig. 1 it will be understood that on the closing of the back B the notch D will engage the pin F and become locked by an ordinary lock, and to release the back B after the lid is opened the free ends of the rods C have to be actuated to release the rods from the pins F and allow the back B to be pushed out.

According to Fig. 2 the locking-notches D are dispensed with and the back-rods C continued a little, so that they pass through holes in the lid A and project, so that the lid and the back can be secured by padlocks or other devices being passed through the holes in the ends of the rods. This construction is especially applicable for use at picnics, the receptacle being made of wicker-work, as a basket, and the stand being so made with the folding pivot K out of the center that when the stand is in the position shown the box can be used as a table at which a person could stand to partake of refreshments; but if the stand be turned upside down then the table would be of a height that persons could sit at it to partake of refreshments.

According to Figs. 3 and 4 the back is formed in two pieces B B', the piece B' being shown open; otherwise the construction is the same as Fig. 1. The ends are provided with sockets capable of holding various devices, such as a hooked stem I and a cloth water-basin J, and also with handles P by which such box can be carried. This construction (shown at Figs. 3 and 4) is especially suitable as a kit-box for use by soldiers, yeomanry, horse-trainers, stablemen, and others, as the hooked rod may be employed for hanging the bridle and other appliances. The saddle may be placed across the box at the closed portion and the work—such as cleaning, brushing, or polishing—may be done on the table portion B'.

The box or basket may be provided with partitions for containing articles, such partitions being arranged according to the intent of use to which such an article is intended.

The stand can be carried in the box, as also may camp-stools and like articles.

What I claim, and desire to secure by Letters Patent, is—

1. A box having a hinged back and a hinged lid mounted for movement into a common plane to constitute a table, and means housed by the box for holding the back and lid in 5 such common plane.
2. A box having a hinged back and a hinged lid mounted for movement into a common horizontal plane to constitute a table, combined with rods connected to the said hinged 10 back and hinged lid respectively, having notches, the box being provided with pins to enter said notches to hold the back and lid in said common horizontal plane.
3. A box having a hinged back and a hinged

lid mounted for movement into a common 15 plane to constitute a table, one of said parts consisting of a plurality of sections one of which is adapted to be moved independently of the other, combined with means housed by the box for holding the back and lid in said 20 common plane.

In testimony whereof I have hereunto set my hand in presence of two subscribing witnesses.

WALTER WILLIAM WALKER GREEN.
